UNITED STATES PATENT OFFICE.

SAMUEL PARK HODGEN, OF PITTSFIELD, ILLINOIS.

BRACE FOR GATES.

SPECIFICATION forming part of Letters Patent No. 443,996, dated January 6, 1891.

Application filed July 16, 1890. Serial No. 358,887. (No model.)

To all whom it may concern:

Be it known that I, SAMUEL PARK HODGEN, a citizen of the United States, residing at Pittsfield, in the county of Pike and State 5 of Illinois, have invented a new and useful Brace for Gates, of which the following is a specification.

The invention relates to improvements in braces for gates.

10 The object of the present invention is to provide a simple and inexpensive brace adapted to be readily applied to a gate of the ordinary construction, more particularly to brace old dilapidated ones, and capable of being readily tightened from time to time to prevent sagging.

15 The invention consists in the construction and novel combination of parts hereinafter fully described, illustrated in the accompanying drawings, and pointed out in the claim hereto appended.

20 In the drawings, Figure 1 is a side elevation of a gate provided with a brace constructed in accordance with this invention. Fig. 2 is a plan view. Figs. 3 and 4 are detail views 25 of the wedge and the wear-plate.

Referring to the accompanying drawings, 1 designates a gate of ordinary construction comprising the instile 2, the outstile 3, and 30 horizontal rails or bars 4, and supported by a brace 5, constructed of a single piece of wire extending diagonally around the gate from the inner upper end thereof toward the lower outer end. Interposed between the 35 wire brace and the outer face of the outstile is a wedge 6, and when the gate sags so that it does not latch as it should, by holding the outer end of the gate up in its proper position with one hand and with a hammer driv-

ing the wedge downward the brace will be 40 tightened and securely hold the gate in its proper position. The wire brace 5 takes the place of the ordinary inclined brace of a gate, and the wedge 6 is constructed as illustrated in Figs. 1 and 3 of the accompanying drawings, 45 having its inner face, which lies adjacent to and in contact with the outstile, curved. A wooden wedge or a metal plate may be employed, and in all cases the wedges and plates used are as wide or of greater width than the 50 outstile to prevent the wires coming in contact therewith. The semi-oval wedge is adapted to be readily moved upward and downward, and is provided in its flat face 8 with a notch or groove 9 to receive the brace. The instile 55 2 has secured to one of its faces—the one adjacent to the hinge-post—a metal plate 7, which is interposed between the said stile and the brace and serves as a wear-plate or bearing to prevent the brace from becoming 60 embedded in the gate. The plate 7 at the upper inner end of the gate may, if desired, be omitted.

Having thus described my invention, I claim—

65 The combination of the gate, the brace constructed of wire and encircling the gate diagonally, and the semi-oval wedge provided with a groove or indentation to receive the brace and adapted to be driven downward, 70 substantially as described.

In testimony that I claim the foregoing as my own I have hereto affixed my signature in presence of two witnesses.

SAMUEL PARK HODGEN.
